United States Patent Office

Des. 181,333
Patented Nov. 5, 1957

181,333

PLATE OR SIMILAR ARTICLE

A. Baker Barnhart, New York, N. Y., assignor to The Lucent Corporation, New York, N. Y.

Application November 14, 1956, Serial No. 43,759

Term of patent 14 years

(Cl. D44—15)

The figure is a plan view of a plate or similar article, of conventional configuration, showing my new design.

I claim:

The ornamental design for a plate or similar article, as shown and described.
